UNITED STATES PATENT OFFICE.

GEORGE W. RAY, OF INDIANAPOLIS, INDIANA.

LAMP-DIMMER.

1,263,288.

Specification of Letters Patent. Patented Apr. 16, 1918.

Application filed October 10, 1917. Serial No. 195,778.

To all whom it may concern:

Be it known that I, GEORGE W. RAY, a citizen of the United States, residing at Indianapolis, Marion county, and State of Indiana, have invented and discovered certain new and useful Improvements in Lamp-Dimmers, of which the following is a specification.

My invention relates to dimmers for automobile lamps; and its object is to provide a device of this class having means for so interrupting and deflecting the rays of the light as to prevent glare while at the same time preserving the full strength of the illumination upon the road ahead from the rays projected from the lower part of the lamp and increasing such illumination by adding to the lower rays substantially the full strength of the rays above the center of the lamp.

With this object in view, my invention is embodied in preferable form in the device hereinafter described and illustrated in the accompanying drawings.

In these drawings, Figure 1, is a front full size view in elevation of the dimming device; Fig. 2, a side view in elevation thereof, and Fig. 3, a reduced vertical section of the lamp showing the device applied thereto.

Referring to the drawings, 1 indicates the lamp bulb, 2 the casing, 3 the deflector and 4 the lens. The glare preventing device constituting my invention is adapted to be mounted within the lamp and behind the lens, and it comprises a series of thin fixed translucent plates or slats 5 of soft wood spaced apart vertically at equal intervals and having their front edges bearing against or located adjacent to the lens and extending rearwardly from said lens at an upward angle, preferably at an angle of substantially 28° to the plane of the lens, and which slats extend from a point near the upper end of the lens to a point substantially opposite the center of the lamp bulb and which have non-lustrous surfaces and are preferably made of non-metallic, light-absorbing material. These slats are made of wood in its natural state unpolished and unvarnished, and poplar wood has been found to be the most suitable for this purpose. The slats are fixed on vertical supporting bars 6, preferably by engagement with angular slats 7 formed in the bars, in which the slats are held by glue; or other

suitable means of locking the slats to the bars in angular position may be provided. Secured to the upper ends of the bars is a top slat 8 having its surface lying in vertical planes and constituting a supporting member for the frame formed of the bars and slats. Secured to this upper supporting member by being clenched thereon or otherwise engaged therewith, is a hanger 9, 60 preferably consisting of pliable metal and adapted to be clamped between the lens 4 and the inwardly turned flange of the casting or shell 2, whereby the frame is vertically suspended.

The rays of light projected from the upper part of the bulb and from the upper half of the deflector will be interrupted by the deflector slats 5 and downwardly deflected upon the road and owing to the angular inclination of said deflector members, the greater part of the illumination from the upper half of the reflector will be preserved and will serve to add its lighting effect to the illumination from the lower half 80 of the lamp, upon the road ahead where it is needed while at the same time the projection of glaring rays from the reflector bulb is avoided. Owing to the material of which the slats are composed and the non-lustrous 85 surfaces thereof no glare will be imparted by the slats themselves while at the same time because of their thin cross section and such material a considerable degree of light, but of a soft character, will be diffused through 90 them and at the same time the full illuminating effect from the bulb below the center thereof will be obtained, giving a strong light upon the road for a long distance 95 ahead.

Having thus described my invention, what I claim is:—

1. In combination with a lamp and its reflector and lens, glare preventing means for said lamp comprising a series of slats in front of the lamp bulb and reflector arranged angularly to the plane of the lens and extending upwardly from said plane, said slats being of thin translucent wood having unpolished non-lustrous surfaces.

2. In combination with a lamp including its reflector and lens, glare preventing means comprising thin, translucent slats of soft, unpolished and unfinished wood arranged in front of the lamp bulb and behind the lens and disposed in a vertical series extending from substantially the

center of the said bulb to the upper border of the lens, said slats being spaced apart and inclined upwardly and rearwardly to the plane of the lens, means for supporting 5 said slats, and means for attaching said supporting means to the lamp structure.

In witness whereof, I have hereunto set

my hand and seal at Indianapolis, Indiana, this 8th day of October, A. D. nineteen hundred and seventeen.

GEORGE W. RAY. [L.S.]
